UNITED STATES PATENT OFFICE.

CHARLES BRANSTON HUNT, OF LONDON, ENGLAND.

SEWING-MACHINE.

SPECIFICATION forming part of Letters Patent No. 476,647, dated June 7, 1892.

Application filed February 10, 1892. Serial No. 420,973. (No model.) Patented in England August 18, 1890, No. 12,959; in France January 5, 1891, No. 210,601; in Belgium January 8, 1891, No. 93,367; in Germany January 16, 1891, No. 60,930; in Italy January 28, 1891, XXV, 29,012, LVII, 61, and in Austria-Hungary May 18, 1891, No. 4,544 and No. 16,860.

To all whom it may concern:

Be it known that I, CHARLES BRANSTON HUNT, a subject of the Queen of Great Britain, residing at 59 Holborn Viaduct, London, 5 England, have invented new and useful Improvements in Sewing-Machines, (for which I have obtained Letters Patent in Great Britain, No. 12,959, dated August 18, 1890; in France, No. 210,601, dated January 5, 1891; 10 in Belgium, No. 93,367, dated January 8, 1891; in Germany, No. 60,930; dated January 16, 1891; in Italy, Vol. XXV, 29,012, Vol. LVII, 61, dated January 28, 1891, and in Austria-Hungary, No. 4,544 and No. 16,860, dated 15 May 18, 1891,) of which the following is a full, clear, and exact specification.

This invention relates to that type of sewing-machines which can be employed at the will of the operator to form a lock-stitch or a 20 chain-stitch.

The objects of my invention are to provide novel means for producing ordinary lock-stitches, ordinary chain-strokes, and 25 stitches termed "chain locked stitches," and to provide novel, simple, and efficient means for throwing the lock-stitch mechanism out of action and the chain-stitch mechanism into action, and conversely.

To accomplish all these objects my invention involves the features of construction and the combination or arrangement of devices 30 hereinafter described and claimed, reference being made to the accompanying drawings, in which—

35 Figure 1 is a central vertical sectional view taken longitudinally through the machine. Fig. 2 is a bottom plan view of the same. Fig. 3 is a similar view omitting the under reel-carrier. Fig. 4 is a transverse sectional view taken on the line $\alpha\alpha$, Fig. 3. Fig. 5 is a detail sectional elevation showing the under reel-carrier. Figs. 6, 7, 8, 9, 10, and 11 are detail views of parts hereinafter explained. Fig. 12 is a detail sectional view showing the 40 looper-beams, the cam for moving one beam lengthwise relatively to the other, and a portion of the under shaft. Fig. 13 is a detail transverse sectional view taken on the line 45

yy , Fig. 3; and Fig. 14 is a similar view taken on the line zz , Fig. 3, showing by dotted lines 50 the pendent arm which carries the stud or roller.

In order to enable those skilled in the art to make and use my invention, I will now describe the same in detail, referring to the 55 drawings, wherein—

The numeral 1 indicates the bed-plate of a sewing-machine; 2, the overhanging arm containing a main drive-shaft 3, which reciprocates the needle-bar 4 and operates the take-up 60 5 and presser-bar 6 in any well-known manner. The drive-shaft connects by a pitman 7 or otherwise with a horizontal shaft 8, journaled in suitable bearings under the bed-plate, all in such manner that when the drive-shaft is turned the take-up, the presser-bar, and the needle-bar are actuated and the under shaft 8 revolves.

The under shaft is provided with a cam 9, engaged with the cam-strap 10 of an arm 12, 70 which is jointed to one extremity of a horizontal vibratory lever 13, pivoted between its extremities, as at 14, to the bed-plate. The opposite end of the vibratory lever is provided with a fork 15, engaging a detachable 75 pin or bolt 16 on a slide 17, adapted to move in a horizontal plane transversely to the length of the under shaft. The transversely-moving slide 17 is provided with a groove 17^a, Fig. 7, which engages a suitable guide-rib 18, 80 secured to or formed with a plate 19, Fig. 6, detachably secured to the bed-plate, and which is arranged on its upper surface flush with the cloth-plate 20 and the usual slide-plate 21.

The transversely-movable slide 17 is provided at its outer end with a thumb or finger piece 22, by which it can be slid outwardly toward the rear side of the bed-plate when the forked end 15 of the vibratory lever 13 is 90 disengaged from the slide by detaching the pin or bolt 16. The inner end of the slide 17 is provided with a pair of elastic fingers 23, Figs. 6 and 7, formed with lateral lips or tongues 24, which project toward each other 95 and normally touch so that when the slide

moves inward in the direction of the arrow, Fig. 6, the lips or tongues pass through the loop formed by the needle and a looper hereinafter explained and hold such loop, while 5 the take-up tightly draws the upper or needle thread. As the slide is moved outward by the vibratory lever 13 the lips or tongues 24 are pressed apart by coming in contact with the needle, so that the needle and loop 10 can escape.

The cloth-plate 20, Fig. 6, is formed with a pair of parallel slots 25, in which move the toothed plates 26 of a feed-dog 27, Fig. 10, so that the fingers reciprocate between said 15 toothed plates 26.

The feed-dog 27 is secured to a rod or bar 28, carried by upwardly-projecting arms 29 of a rock-shaft 30, so that when the latter is rocked the arms 29 are vibrated and the rod 20 or bar 28 is moved lengthwise to reciprocate the feed-dog. The up-and-down motion of the feed-dog is effected by the lateral arm 31 of a rock-shaft 32, actuated by a cam 33 on the under shaft 8 engaging a second lateral arm 34 on the shaft 32 in such manner, and when 25 the under shaft 8 is revolved the cam 33 vibrates the arm 34 to rock the shaft 32, and thus raise and lower the rod or bar 28, while the latter is moved lengthwise by the arms 30 of the rock-shaft 30. The shaft 30 is rocked by means of an arm 35, having a forked end embracing a cam 36 on the under shaft 8. The arm 35 is rigid with a bar 37, journaled at its ends in lateral studs 38, formed with the rock-shaft 30, which operates the rod or bar 28. The arm 35 is provided with a guideway 39, engaged with a stud, pin, or roller 40, secured to a pend- 35 ent bracket 41, formed with or attached to a lengthwise-movable rack 42, which engages a 40 pinion 43 on the lower end of a vertical spindle 44, having a suitable crank or other han- 45 dle 45, by which to turn it for the purpose of moving the rack and adjusting the stud or roller 40 along the guideway 39. The stud 45 or roller 40 constitutes the fulcrum of the arm 35, and when the cam 36 operates such arm 35 the latter is oscillated in a vertical plane to rock the shaft 30. By operating the handle 45 the rack 42 is moved lengthwise to 50 adjust the stud or roller 40 in the guide 39, and consequently the stroke of the arm 35 can be varied for the purpose of increasing or diminishing the extent to which the arm 28 is moved lengthwise. By this means the hori- 55 zontal-stroke of the feed-dog can be varied for regulating the length of the stitches.

The bed-plate 1 is provided with a hanger 46, containing a bushing 47, through which the under shaft 8 extends. The bushing 47 60 is provided with a cam 48, on which is centrally mounted a beam 49. The shaft 8 is adapted to rotate in the bushing 47, and on its outer end 50 is centrally mounted a beam 51. The beam 51 is provided at one end with 65 a tubular projection 52 for carrying a stem 53, having at one end a looper 54 and at the

opposite end a disk or head 55, provided with a slot 56, engaged with a stud 57 on one end of the beam 49, so that as the beams are rotated the stud 57 slides back and forth in the slot 70 56, and thereby turns the looper 54 into the proper position for taking each loop in succession and for throwing such loop off in the required manner. The lower end of the beam 51 is provided with a stud 58, adapted to 75 move in a guideway 59 at the end of the beam 49 opposite the end which carries the stud 57, all in such manner that as the under shaft 8 revolves and turns the beam 51 the beam 49 is also turned, and through the me- 80 dium of the cam 48 is slightly moved length- wise, so that the stud 57 operates on the disk or head 55 of the looper-stem 53 to turn the looper 54, as before stated. As the looper-beam 51 is secured to the shaft 8 and the 85 looper-beam 49 is mounted on the cam or eccentric 48, it will be obvious that as the shaft 8 revolves the looper-beam 49 will be slowly reciprocated lengthwise independent of the looper-beam 51, so that the looper-stem 53 is 90 oscillated for swinging or canting the hook 54 forward as it approaches the needle and backward as it continues its movement past the needle.

The lower thread is on a reel or spool located in a case or cage 60, removably ar- 95 ranged in a reel-case carrier 61, pivoted to a bracket 62, depending from the bed-plate.

The carrier and reel case are not herein more fully described and shown, as they con- 100 stitute the subject-matter of my application for Letters Patent filed June 12, 1891, Serial No. 396,031.

In operation as the elastic fingers 23 recede from the needle-hole 62 in the cloth-plate 20 105 the looper 54 approaches the needle and takes the thread to form the loop and then the elastic fingers advance and the lips or tongues 24 thereof enter the loop. As the looper con- 110 tinues its rotary movement the looper-stem 53 110 is oscillated to cant the looper backward for throwing off the loop. The take-up then oper- 115 ates and as the lips or tongues 24 are in the loop they hold the same while the take-up tightly draws the upper thread. To indicate 120 the length of the stitches, the handle 45 of the pinion-spindle 44 carries a pin or pointer 63 to co-operate with a properly-graduated disk 64, fixed to the upper side of the bed-plate.

In using the machine for lock-stitch sewing 120 the thread of the lower or under reel is em- 125 ployed, as usual, in conjunction with the up- per or needle thread, whose loop is carried by the looper round the lower reel-cage for each stitch, the elastic fingers 23 being first thrown out of action by disengaging the forked end of the vibratory lever 13 from the slide 17 and then moving the latter outward toward the rear of the bed-plate 1 through the medium of the finger-piece 22.

For chain-stitch sewing the lower reel-thread 130 is thrown out and the slide 17 is engaged with

the forked end of the vibratory lever 13, while for lock-chain-stitch sewing the lower reel-thread is thrown in to co-operate with the upper or needle thread while the chain-stitch is being made.

Having thus described my invention, what I claim is—

1. In a sewing-machine, the combination, with the bed-plate, a reciprocating needle-carrying bar, a rotary looper, and a lower reel-carrier, of a transversely-movable slide arranged under the bed-plate and having elastic fingers provided with inwardly-projecting lips or tongues, a vibrating lever moving in a horizontal plane parallel with the bed-plate and having a forked extremity, a device detachably connecting the forked extremity of the lever to the slide, a rotary under shaft having a cam and supporting the looper, and an arm jointed at one extremity to the lever and having at its opposite extremity a cam-strap encircling the cam on the under shaft, substantially as described.

2. The combination, with a needle-carrying bar, of a rotary under shaft, a pair of loosely-connected looper-beams rotated by the shaft, a looper having an axially-oscillating stem carried by one looper-beam and engaged by the other looper-beam, and means for moving the latter lengthwise as it rotates for axially

oscillating the looper-stem, substantially as described.

3. The combination, with a needle-carrying bar, of a rotary under shaft, a pair of loosely-connected looper-beams rotated by the shaft, 35 a looper having an axially-oscillating stem carried by one looper-beam and engaged by the other looper-beam, and a cam on the under shaft for moving the latter beam lengthwise as it rotates for axially oscillating the 40 looper-stem, substantially as described.

4. The combination, with a needle-carrying bar, of a rotary under shaft, a pair of loosely-connected looper-arms rotated by the shaft, a looper having an axially-oscillating stem carried by one looper-beam and provided with a grooved disk or head engaged by a part of the other looper-beam, and a cam on the under shaft for moving the latter beam lengthwise as it rotates for axially oscillating the 50 looper-stem, substantially as described.

In witness whereof I have hereunto signed my name, in presence of two subscribing witnesses, this 15th day of September, 1891.

CHARLES BRANSTON HUNT.
